UNITED STATES PATENT OFFICE.

WALTER K. VOSS, OF DAVENPORT, IOWA.

WASHING MACHINE.

Application filed January 19, 1927. Serial No. 162,015.

The present invention relates to washing machines and parts thereof.

Among the objects of the invention is to provide a novel operating mechanism for a washing machine, such as for an agitator or dolly in a tub of a clothes washing machine, and preferably of a type where part of the operating means is associated with or carried by a movable cover portion or section of a cover top of the tub, such that when the cover is closed, the operating mechanism will be in operative condition and when in open position, the driving connection will be broken or the like. In a specific illustrative embodiment of the invention, this is effected by the cleaving of a pair of gears of which one is a driver and mounted upon a shaft at the side of the tub and the other is a driven element rotatably carried by the cover, so that when the cover is opened, the latter gear is disconnected from the former by the sliding of the teeth thereof, and likewise when the cover is closed, to establish the enmeshment of such teeth. The driver is preferably housed in a housing rigidly secured to the tub, as at one side thereof, and the operating means is preferably located below the cover top. This latter is also an object of the invention, and also may include the idea of a housing therefor connected to the underside of such cover. The cover is preferably a raised cover resting upon the rim of the tub and including a space within such cover and above the rim of the tub, for the inclusion of the operating mechanism for the agitator or dolly which may be both rotatably and slidably carried by the cover. In this way the top of the cover may be plain, flat and smooth without projections, bulges and the like.

The invention also comprehends the provision of a novel cover or top for the tub, which may be of raised type or form as above indicated, and having a movable portion or swinging section, and a fixed portion or section secured to the tub. The two sections or portions are preferably cut concentric to the axis of the hinge thereof, such that the top may swing about the axis of the hinge with a part dipping below the top and the top resting laterally against the fixed section when the cover is in open position. It also includes means for pivotally or hingedly supporting the movable section, preferably with the hinge below the cover top and in advance of the parting therebetween, so as to leave

the top flat and smooth without projecting portions of the hinge shown at or above the top of the cover when the cover is closed.

Other objects, advantages, capabilities and features are comprehended by the invention as will later appear and are inherently possessed thereby.

Referring to the drawings, Fig. 1 is a view in vertical elevation of a washing machine constructed in accordance with the invention.

Fig. 2 is a fragmentary top plan view of the same showing the cover in open position.

Fig. 3 is a part top plan view and part horizontal section of the machine showing the cover in closed position in the device in operative condition.

Fig. 4 is a vertical sectional view taken in planes represented by line 4-4 in Fig. 3 of the drawings.

Fig. 5 is a fragmentary part plan and part horizontal sectional view of a driving portion of the machine.

Fig. 6 is a fragmentary vertical sectional view through a part of the tub of the machine.

Fig. 7 is a fragmentary vertical elevational view of a driving part of the operating mechanism.

Referring now more in detail to the drawings, an illustrative embodiment of a washing machine embodying the invention is shown as comprising a tub 1 mounted upon a support 2 carrying casters 3 whereby the machine may be moved about readily over a surface. Within the support 2 is carried, in any suitable manner, power operating mechanism adapted to drive through a vertical shaft 4 rotatable in a housing 5 suitably mounted upon the support. The shaft 4 has driving connections through reversing gearing for a wringer 6 which is capable of swinging about a vertical axis in any desired position, the reversing gearing being enclosed in a housing 7 connected to the wringer and removably mounted above the housing 5. The support may also carry a shelf or bracket 8 of the collapsible type and designed to support a basket or tub or the like.

The top of the tub has a rim portion 9 upon which may rest a raised cover having a fixed cover portion 10 and a movable cover portion 11. These cover portions have vertical side walls 12 terminating in horizontal flanges 13 secured to the tub rim and extend-

ing upwardly to the top portion 14 of the fixed cover portion 10 and the top of the cover portion 11. It will be observed that the top is cut on a curved, bias or in an arc forming a parting 15 between the fixed and movable sections. In order that the movable top may be hinged to swing so that it will not interfere with the fixed section at the parting 15, hinge mechanism comprising members 16 are secured to the side and top walls 12 and 14 of the fixed section by means of screws, bolts or the like 17 and 17', and carry curved or bent arms 18 having at the other ends thereof hinge parts pivotally connected to hinge parts in plates 18^a secured to the under surface of the top 11 as by means of screws, bolts or the like 19. The axis of the hinge member is located in advance of the parting 15 so that the rear edge portion of the top 11 may dip, and when the cover is swung back, the top portion in front of the hinge axis may contact or abut against the front edge of the fixed section 14, as shown by dotted lines in Fig. 4. When the movable part 11 is closed, the edges at the parting 15 will come into contact or coincidence as also shown in full lines in Fig. 4.

The cover, as a whole, is raised to form a hollow space beneath it and above the rim of the tub for the carrying of suitable operating mechanism adapted to operate a dolly or agitator 20 in the tub. This dolly may be of the type that is capable of floating or being carried at the level of the contents of the tub and is preferably connected to a non-circular shaft 21 slidably mounted in a pinion member 22 rotatably carried in bearings 23 in the cover 11 and 24 in a housing 25 depending from the bottom surface of the cover 11 and secured thereto by suitable securing means such as bolts or the like 26. The shaft 21 is capable of sliding vertically so that the dolly may float or rest upon the contents of the tub and yet be caused to rotate or have an alternating rotary movement with the pinion 22. The housing 25 encloses a space within which a part of the operating mechanism is enclosed. The operating mechanism comprises a reciprocating rack 27 adapted to engage with the teeth of the pinion, and connected at its other end pivotally to a driven gear 28 rotatably mounted upon a stud bearing 29 having a stud 30 secured to a depressed portion 31 of the housing 25, as clearly shown in Figs. 3 and 4 of the drawings. In order to hold the rack constantly in mesh engagement with the pinion 22, there may be provided a flanged roller or the like 32 rotatably mounted on a stud 33 secured to the lower wall of the casing or housing 25, the rack being slideable between the flanges of the roller and being held by the body of the roller in proper engagement with the pinion 22. The cover 11 is provided with an opening 34

through which may extend a portion of the gear 28 beyond the periphery of the cover and tub for engagement therewith of a driving gear 36 secured to the upper end of the shaft 4 as by a cross-pin 37 or the like. The upper end of the housing 5 is also provided with a housing 38 for enclosing the gear 36 and other parts, this housing being secured to the upper end of the housing 5 as by bolts or the like 39, and also may be fastened by way of integral portions 41 to the rim 9 of the tub. In this way the structure may be made rigid with the tub. The housing 38 also has a cover 42 which may be connected to the housing portion 38 as by way of screws, bolts or the like 43, and by way of lugs 40 to the portion 41 of the housing 38. This cover is preferably provided with a cut-out portion 44, of arc shape or the like, for exposing a part of the teeth of the gear 36 as well as the teeth of the gear 28. The top of the cover 11 is also provided with a cut-out 45 for the same purpose. By providing these cut-out portions, the operator can see the relative position of the teeth when the cleaving thereof is effected as well as permitting the movement of the cover 11 with the gear 28 when opening or closing the cover and moving the gear 28 from or into sliding engagement with the teeth of the gear 38. In order to protect and cover the same, the cover 42 may have a sliding covering member 46 capable of sliding in an arc path on the cover 42 to a position such as that shown in Fig. 3 of the drawing, the same being guided in its movement by guide elements 47 engaging with the periphery of the cover 42, and a pin 48 capable of sliding in a slot 49 of arc shape in the cover 42. It will be noted that the cover member 46 has an arc-shaped cut-out portion 50 such that when the cover is moved to present this cut-out portion opposite the gear teeth, it will permit the cleaving of the gears without interference, and when moved in the position shown in Fig. 3, the cover 46 will cover the gear teeth and extend into the cut-out portion 45 of the cover 11. The cover member 46 may be provided with a projection 51 for the manual engagement thereof for moving the cover in a direction and to a position whereby the cut-out portion 50 may be presented over the gear teeth. The return of the cover 46 is automatically effected by means of a spring 52 connected at one end to the pin 48 and at the other end to a fixed part of the cover 42, the spring surrounding a depending sleeve portion 52' of the cover 42.

When the gears are operating there is a tendency to lateral movement of the driven mechanism and the connected parts, such as the cover 11. In order to avoid this, the rim of the tub is provided with abutment lugs 53 and 54 located at the side of the

opening 34 of the cover and adapted to be engaged with abutment lugs 55 and 56 carried by the cover 11 so that when the latter is in closed position, the lugs 55 and 56 will fit closely against the lugs 53 and 54 and therefore prevent any lateral movement to the cover and the parts carried thereby. This will take the load of lateral thrust off of the hinges of the cover. The upper 10 end of the shaft 4 is connected, as above stated, to the gear 36, the latter having a depressed web portion 57 and a central hub portion 58. The upper end of this hub portion is slotted to form a clutch connection 15 with a cross-pin 59 in a wringer shaft 60, the latter acting as a driving element for the reverse gearing for the wringer. The gear housing 7 of the wringer has a depending socket 61 adapted to slide and fit into and be 20 also rotatable within a sleeve or hub portion 62 forming an integral part of the housing top or cover 42 and the sleeve portion 52', as clearly shown in Fig. 4 of the drawing. The wringer with the housing 7 and sleeve 61 25 may be bodily removed or inserted in place together with the shaft 60, the latter automatically engaging with the clutch end 63 of the hub 58 of the gear 36. Other suitable means are also provided for locking the 30 wringer in swung position such as a locking bar 64 adapted to engage in slots 65 in a plate 66 secured to the top of the housing cover 42.

In the operation of the machine, the power 35 mechanism operates the shaft 4 through the gear 36. Assuming that the contents of the tub have been included therein and the cover brought into closed position, whereby the operator has operated the cover member 46 40 to expose the gear teeth, the teeth of the gear 28 will be brought into sliding engagement with the teeth of the gear 36 so that they will mesh, as the cover is brought into lowered position. As the cover 11 is brought 45 into lowered position, its lugs 55 and 56 will fit closely in between the lugs 53 and 54 so that the cover will be properly centered as well as be prevented from moving laterally when the power is operating through the operating 50 mechanism. The gear 36 will thus drive or rotate the gear 28 which in turn will operate through the reciprocating rack 27, the latter acting to rotate the pinion 22 with an alternate rotary movement and 55 hence likewise through the shaft 21 and the dolly 20. The upper end of the shaft 21 may be provided with a knot 66 whereby the dolly may be manually raised if desired. At the same time the shaft 4 may operate 60 through the clutch 63 and 59 and shaft 60 to the wringer rolls. Also the wringer may be swung to any desired position over the tub.

After the washing operation, the operator 65 may slide the cover member 46 to the point

where it may expose the cut-out portions over the gear teeth and the operator may then raise the cover 11 so as to slidably disengage the gear 28 from the teeth of the gear 36. This will disconnect the driving 70 connection to the operating mechanism for the dolly. The cover may then be swung up into upright position as shown in dotted line in Fig. 4, until the connecting brackets 18 of the cover hinge contact with the edge 75 67 of the fixed cover portion 10 of the top, the cover then remaining in upright position. It will be noted from Fig. 2 that this cover with the attached operating mechanism and dolly will be to one side of the 80 space swept by the wringer when swung from one position to another on one side or the other side of the tub as shown by the dotted line 68 in Fig. 2 of the drawing showing the maximum sweep of the end of the 85 wringer. The cover is preferably hinged on an axis parallel to one end of the support 2 and the operating mechanism in the latter operates through a shaft 4 preferably located at a corner or near a corner of the support 2. This provides for the wringer swinging about an axis whereby the wringer may operate at one side of the tub, at one side of the support, or at another side of the tub and at an end of a support where a tub 90 or basket may be readily carried by the supporting bracket 8.

While I have herein described and upon the drawings shown a particular illustrative embodiment of the invention, it is to be understood that the latter is not limited thereto but may comprehend other constructions, arrangements of parts, details and features without departing from the spirit thereof.

Having thus disclosed the invention, 100

I claim:

1. In a washing machine comprising a tub, a cover for the tub and carrying means for operating an agitator in the tub, driving means adjacent the tub and cover and associated with the operating means to drive the same when the cover is in closed position, and means on the tub and associated with the cover to laterally brace said cover.

2. In a washing machine comprising a 110 tub, a cover for the tub and carrying means for operating an agitator in the tub, driving means adjacent the tub and cover and associated with the operating means to drive the same when the cover is in closed position, and a projection on said tub to cooperate with said cover to prevent lateral movement of the cover when in closed position.

3. In a washing machine comprising a 125 tub, a cover for the tub and carrying means for operating an agitator in the tub, driving means adjacent the tub and cover and associated with the operating means to drive the same when the cover is in closed position.

tion, and lugs on the tub and engaging said cover to prevent lateral movement thereof.

4. In a washing machine comprising a tub, a cover for the tub and carrying means for operating an agitator in the tub, driving means adjacent the tub and cover and associated with the operating means to drive the same when the cover is in closed position, the adjacent portion of said cover having shoulders, and lugs on said tub located to engage said shoulders when the cover is closed to laterally brace the cover.

5. In a washing machine comprising a tub, a cover for the tub and carrying means for operating an agitator in the tub, driving means adjacent the tub and cover and associated with the operating means to drive the same when the cover is in closed position, said operating means being disengaged from the driving means when the cover is opened, and means for covering the engaging portions of said driving and operating means when the cover is in closed position.

25 6. In a washing machine comprising a tub, a cover for the tub, operating means associated with the cover for operating an agitator in the tub, driving means associated with the tub and having a driving member located to operate said operating means when the cover is in closed position and to be out of operating relation when the cover is in open position, and movable means for covering the engaging portions of said driving means and said operating means when in operative connection, and adapted to be moved to clear the same when the cover is opened.

7. In a washing machine comprising a tub, a cover for the tub, operating means associated with the cover for operating an agitator in the tub, driving means associated with the tub and having a driving member located to operate said operating means when the cover is in closed position and to be out of operating relation when the cover is in open position, housings for said driving member and said operating means and having cut-away portions at the locus of operative connection between said driving member and the operating means whereby the cover may be moved to and from closed position.

8. In a washing machine comprising a tub, a cover for the tub, operating means associated with the cover for operating an agitator in the tub, driving means associated with the tub and having a driving member located to operate said operating means when the cover is in closed position and to be out of operating relation when the cover is in open position, housings for said driving member and said operating means and having cut-away portions at the locus of operative connection between said driving mem-

ber and the operating means whereby the cover may be moved to and from closed position, and cover means for normally closing said cut-away portions and adapted to expose the same when the cover is moved to or from closed position.

9. In a washing machine comprising a tub, a cover for the tub, operating means associated with the cover for operating an agitator in the tub, driving means associated with the tub and having a driving member located to operate said operating means when the cover is in closed position and to be out of operating relation when the cover is in open position, housings for said driving member and said operating means and having cut-away portions at the locus of operative connection between said driving member and the operating means whereby the cover may be moved to and from closed position, and a sliding member on the housing for said driving member for normally covering said cut-away portions.

10. In a washing machine comprising a tub, a cover for the tub, operating means associated with the cover for operating an agitator in the tub, driving means associated with the tub and having a driving member located to operate said operating means when the cover is in closed position and to be out of operating relation when the cover is in open position, housings for said driving member and said operating means and having cut-away portions at the locus of operative connection between said driving member and the operating means whereby the cover may be moved to and from closed position, a sliding member on the housing for said driving member for normally covering said cut-away portions, and a spring in said housing and connected to said sliding member to return the same to normal position.

11. In a washing machine comprising a tub, a cover for the tub, means carried by the cover for operatively holding an agitator in the tub, reciprocatory operating means carried by the cover and beneath the same whereby the top of the cover is smooth, and means associated with the tub and said operating means for operating the latter.

12. In a washing machine comprising a tub having a rim, a cover therefor having a flat top and a depending rim portion having means for engagement with the rim of the tub, a housing connected to the underside of the top and providing a space therebetween, and means in said space for producing a reciprocatory movement and adapted to operate an agitator in the tub.

13. In a washing machine comprising a tub having a rim, a raised cover on said rim and providing a space beneath the cover and above said rim, an agitator operatively carried by said cover to operate in said tub, and means located in said space for produc-

ing a reciprocatory movement and connected to said agitator.

14. In a washing machine comprising a tub having a rim, a raised cover on said rim and providing a space beneath the cover and above said rim, an agitator operatively carried by said cover to operate in said tub, means located in said space for producing a reciprocatory movement and connected to said agitator, and a housing secured to the underside of said top and enclosing said reciprocating means.

15. A washing machine comprising a support, a tub on the support, operating means carried by the support and having a driving member associated with the tub, and a housing for said member and being rigidly secured to said tub, an agitator in the tub, driven means operated by said member and carried by the tub, said housing having a cut-away portion to expose the engaging portions of said member and operating means.

16. A washing machine comprising a support, a tub on the support, operating means carried by the support and having a driving member associated with the tub, a housing for said member and being rigidly secured to said tub, an agitator in the tub, driven means operated by said member and carried by the tub, said housing having a cut-away portion to expose the engaging portions of

said member and operating means, and a movable cover for said cut-away portion.

17. A washing machine comprising a support, a tub on the support, operating means carried by the support and having a vertical shaft at the side of the tub, a gear secured to the upper end of said shaft, a cover for the tub, an agitator carried by the cover and operable in the tub, means carried by the cover for producing a reciprocatory movement, said means driven by said gear, and a housing secured to the underside of said cover and for enclosing said reciprocating means.

18. A washing machine comprising a support, a tub on the support, operating means carried by the support and having a vertical shaft at the side of the tub, a gear secured to the upper end of said shaft, a cover for the tub, an agitator carried by the cover and operable in the tub, means carried by the cover for producing a reciprocatory movement, said means driven by said gear, a housing for said shaft and gear and rigidly secured to said tub, and a housing secured to the underside of said cover and for enclosing said reciprocating means.

In witness whereof, I hereunto subscribe my name to this specification.

WALTER K. VOSS.
